UNITED STATES PATENT OFFICE.

JOHN S. KENNEDY, OF STANHOPE, NEW JERSEY, AND JOHN B. NAU, OF NEW YORK, N. Y.

MIXING-FURNACE FOR IRON-FOUNDRIES.

No. 895,029.

Specification of Letters Patent.

Patented Aug. 4, 1908.

Application filed March 26, 1907. Serial No. 364,596.

To all whom it may concern:

Be it known that we, JOHN S. KENNEDY, residing at Stanhope, in the county of Sussex and State of New Jersey, and JOHN B. NAU, residing at New York, in the county of New York and State of New York, have invented certain new and useful Improvements in Mixing-Furnaces for Iron-Foundries, whereof the following is a specification, reference being had to the accompanying drawings.

In said drawings, Figure I, represents a transverse vertical section through the furnace, indicating in a partial sectional view certain adjacent parts. Fig. II, is a longitudinal vertical section through the furnace on the lines II, II, of Fig. I. Fig. III, is a sectional plan view of the furnace on the lines III, III, of Figs. I, and II.

The object of our invention is to provide for use in foundries a mixing furnace of a type adapted to foundry practice as distinguished from the mixers which have heretofore been used in connection with steel works for the manufacture of the steel itself. Mixers of this last mentioned type are necessarily of large capacity, as hundreds of tons are passed through them every twenty-four hours. In consequence of their requirements a highly complicated and costly structure is necessary, the use of which would be prohibitive in connection with the ordinary foundry practice, where the quantities of the iron dealt with are much smaller and the conditions of use otherwise different.

To meet the ends above noted we have devised a mixer which is of a novel type, in that it is stationary, as distinguished from tilting, and also in other features about to be described. Among these the following may be noted as prominent: The stationary mixer is adapted to receive iron directly from the blast furnace, in relatively large units, as compared with the units of withdrawal, although upon a scale much smaller than that which is characteristic of the tilting mixers heretofore used. Means are also afforded for conveniently adding to the metal of the bath, metal from other sources; for protecting the bath as far as possible against oxidation during the mixing period while maintaining its temperature; and for permitting the withdrawal of the contents of the bath in relatively small units from selected and different levels. The general system therefore comprises, in addition to the furnace proper, regenerative hot blast apparatus, whereby

the temperature may be maintained at a suitable point by the action of flame upon the metal. But certain features of our invention are not essentially dependent upon the use of such specific form of heating apparatus.

Referring to the figures,—1, indicates the hearth of the stationary mixing furnace, and 2, the top and side walls thereof. The hearth and sides are of such dimensions and configuration as to afford a relatively short and deep bath, as compared with the corresponding features of the bath in ordinary open-hearth furnaces. The floor or bottom of the hearth is covered with a lining of refractory brick, the use of which material is essential for a bath having the relatively short and deep dimensions indicated.

The numerals 3, 4, 5, and 6, indicate the flues for providing the necessary flame circulation; said flues communicating in the usual manner with the regenerators 7, and 8, whose stack 9, and controlling valves are conventionally indicated in Fig. I.

At a point preferably midway of the greatest length of the furnace a relatively large charging opening 11, is located in the side wall, said opening having a door or gate 12. Adjacent to said opening is an opening 13, provided with a conducting trough 14, adapted to receive metal from the blast furnace, so as to facilitate charging in relatively large units. These openings are both arranged, as shown, above the normal level of the bath within the furnace. On the opposite side of the furnace, we provide a plurality of superposed tap-holes indicated at 17, 18, and 19, having respectively doors 20, 21, and 22, and spouts or nozzles 23, 24, and 25; these tap-holes being of a size to facilitate the discharge of the contents of the bath in relatively small units.

As will be noted, the opening 18, is at the extreme bottom of the bath, while the openings 17, and 19, are located at varying heights above this region, so that the contents may be tapped at any selected level, to obtain the metal characteristic of the region of such level.

The doors or gates of the various charging and discharging openings may be of any desired character, and it is not necessary to enter into any detailed description thereof.

The object of our invention is, as before stated, to mix and control the character of metal tapped from a blast furnace in rela-

tively large units, permitting the treatment to comprise the addition of other ingredients, such as cold pig iron, scrap, etc.

The flame to be employed is, as far as possible, a neutral one in order to avoid oxidation or undue refining of the metal.

We are of course aware that the use of a mixing furnace is not broadly new, and we do not claim the same.

10 The organization attained by our invention differs however, from previous devices of the same general class in that it is a stationary type and in the peculiar character and configuration of the furnace, as well as 15 in the provision of adjunctive devices which permit complete withdrawal of the bath itself and facilitate the withdrawal of selected portions of its contents.

Having thus described our invention, we 20 claim:

1. A stationary mixing-furnace having a relatively short and deep hearth provided with a closed top, said hearth having a charging aperture and a plurality of tap-holes ar-

ranged at different levels; and means for controlling said charging aperture and said tap-holes.

2. A stationary mixing-furnace having a relatively short and deep hearth provided with a closed top, said hearth having a charging aperture and a plurality of tap-holes arranged at different levels; and means for controlling said charging aperture and said tap-holes, in combination with regenerative heating apparatus communicating with the interior of said hearth.

In testimony whereof, we have hereunto signed our names, in the presence of two subscribing witnesses.

JOHN S. KENNEDY.
JOHN B. NAU.

Witnesses as to John S. Kennedy:

M. T. THOMAS,
J. FRANK BEST.

Witnesses as to John B. Nau:
